UNITED STATES PATENT OFFICE.

WALTER W. ROBINSON, OF BELOIT, WISCONSIN, ASSIGNOR OF ONE-HALF TO BENJAMIN F. LYONS, OF BELOIT, WISCONSIN.

COMPRESSOR VALVE.

Application filed December 27, 1921. Serial No. 524,919.

To all whom it may concern:

Be it known that I, WALTER W. ROBINSON, a citizen of the United States, residing at Beloit, Rock County, Wisconsin, have invented certain new and useful Improvements in Compressor Valves, of which the following is a specification.

The present improvements relate to fluid-compressor construction involving valve means for the passage of the fluid from one side of a reciprocating piston to the other, and thence away from the device. One object is to provide means for mechanically and positively opening and maintaining open throughout a desired interval in the cycle of operations a valve in the piston whereby the fluid may pass freely from one side of the piston to the other without a waste of energy, as in cases where the valve is maintained open by the difference of potential between the two sides, and to overcome also a loss in effectiveness due to a gumming or sticking of the valve parts, and to provide a construction in which substantially the maximum fluid-moving value of the piston stroke is had in each cycle. A specific object is to obtain such advantages according to simple means.

With respect to the outlet valve and cylinder head construction and arrangement herein illustrated and described the chief object is to provide a simple form of construction in which the outlet valve elements may be positioned in a predetermined relative location with respect to the cylinder walls, for instance so as to lie very close to the piston end at the end of its stroke, and be maintained in the desired position regardless of the thickness of packing between the cylinder head and cylinder walls, without prejudice to the easy accessibility and removability of the exhaust valve parts as may be desired.

In the accompanying drawings, which form a part of this specification, Figure 1 is a medial vertical section through a compressor having these improvements embodied therein; Figs. 2, 3 and 4 are horizontal sections on the lines 2—2, 3—3 and 4—4 respectively of Fig. 1; and Fig. 5 is a fragmentary sectional view similar to that of Fig. 1 showing moving parts in various positions.

These improvements are of importance in compressors suitable for the circulation

of a refrigerating medium in a refrigerating system, and the accompanying drawings illustrate a compressor adapted to such use. The compressor shown includes a crank shaft casing 10 having an inlet 11 for the refrigerating medium, cylinder walls 12, a cylinder head 13 held as by screws 14 upon the end of the cylinder walls, and a crank shaft 15 having a crank arm 16 on which is mounted the pitman 17, the other end of the pitman being pivoted upon the pin 18 held between opposite walls of the hollow piston 19, the rotation of the crank shaft 15, as by a motor or any other approved means providing the usual reciprocating motion of the pitman and piston.

The upper end of the piston has a top wall provided with a plurality of fluid-passageway openings 20 therethrough, these openings entering a recess or chamber 21 surrounded by an annular surface 22, the edge of which forms a seat for the flat disc-like valve 23, this valve having an integral stem member 24 loosely positioned for sliding movement in a hole on the axis of the piston.

A leaf spring 25 held by the nut 26 and resting at its ends against a wall formed by opposite openings 27 in the piston maintains the valve 23 upon its seat except when it is mechanically moved away therefrom.

A lever 30 shown as a flat bar inserted through one of the openings 27 and resting against the bottom walls respectively thereof has overlying it a leaf spring 31 resting at its ends on the bar or lever 30 and is bowed away therefrom in the middle, the middle part contacting the end of the stem 24. A cotterpin 32 holds the lever 30 and spring 31 loosely at one end upon the piston whereby the other end of the lever 30 and spring 31 may move upward and downward.

Substantially at right angles to the effective direction of the pitman 17 and adjacent to its pivotal connection to the pin 18 is the projection 34 which constitutes a lever and forms a bearing for the rod or pushing element 35 which is held to the projection by a pin 36 for slight rocking movement. The rod 35 has an adjustable head 37 adapted to engage the under side of the plate or lever 30, this lever 30 and the spring 31 each having a hole whereby the end of the rod 35 may project through these parts loosely and be thereby held in its operative position.

The pitman 17, since it is operated by a crank shaft, has not only a stroke movement which provides a reciprocating stroke movement for the piston, but it necessarily has 5 also a sidewise or rocking movement, and since the projection 34 forms with the pitman 17 a simple substantially right-angled bell crank the sidewise rocking movement of the pitman causes an up-and-down movement of 10 the pin 36 and push rod or pressure-transmitting element 35.

Figure 1 represents the piston in substantially its lowermost position and the pitman is almost at the end of its down stroke, being only slightly to the right of the dead center between the axes of parts 15 and 18. In this position the valve 23 is shown as closed, and it is to be assumed that it has just closed when the pitman is in the relative 20 position shown in Fig. 1. The further movement of the lower end of the pitman to the left as viewed in Fig. 1 will simply draw the head 37 of the push rod farther away from the lever 30, and this will continue until the pitman has reached its extreme movement to the left as viewed in Fig. 1. Thence, as the lower end of the pitman moves toward the right, the head 37 will move again toward the lever 30, and the head 37 will 30 continue to move upward so long as the lower end of the pitman moves from left to right. The head 37 is so adjusted with respect to its associated lever 30 that in its upward movement it will not engage the lever to move it upward until after the piston has reached the extreme upward limit of its stroke, or, in other words until after the lower end of the pitman has passed the upper dead center, or into the relative position 35 illustrated in full lines in Fig. 5, in which position the head 37 is again shown as being in contact with the lever 30 and in which position it is to be assumed that contact has just been made to push the lever 30 upward. As 40 the lower end of the pitman continues to the right as viewed in Figs. 1 and 5 its sidewise or rocking movement lifts the plate 30 more and more, the piston and pitman descending the while. The upward movement of the lever 30 first flattens the spring 31 and then exerts a push upon the stem 24 and thus raises the valve 23 away from its seat and allows the fluid in the crank shaft housing and lower part of the piston (being the low- 50 pressure side of the cylinder) to flow through the openings 20 of the piston into the upper or high-pressure side. After the lower end of the pitman has moved as far to the right as possible, its succeeding movement to the left causes the push rod 35 to descend and the valve 23 gradually to move toward its seat until the relative positions shown in Fig. 1 are again reached, when the valve 23 is closed.

60 According to the construction and ar-

rangement described the valve 23 is mechanically opened on the down stroke of the piston as the device is illustrated, and is maintained closed on the up stroke, the high pressure side receiving fluid on the down stroke, 70 the piston putting it under compression and forcing it out of the cylinder on the up-stroke.

The spring 31 between the valve stem 24 and the lever 30 not only acts to soften the 75 impact of the parts receiving the pushing pressure of the rod 35 but, importantly, it provides take-up means for establishing and maintaining the proper relationship of the several parts without a fitting adjustment, 80 both initially and from time to time, as when the valve and its seat are ground together. The screw driver slot 38 in the valve 23 is provided for such grinding purposes. With successive grindings the end of the stem 24 85 may come materially closer to the lever 30, but this difference is taken up by the spring 31 without any adjustment between those parts. The opening and closing of the valve 23 may be timed by adjusting the head 37 90 on the push rod.

Referring to the upper part of Fig. 1 and Fig. 2, the cylinder walls are recessed at 40 providing an annular seat at 41 to receive the ring-like element 42 having a right- 95 angularly-disposed ring-like seat part or flange 43 defining a passage-way opening 44, the disc-like valve 45 resting on the seat provided by the ring or flange 43. A circular flat plate 46 rests upon an annular shoulder 100 47, the plate 46 having openings 48 along its marginal edge for the passage of fluid, the plate 46 also having an annular downwardly-disposed rib 49 against which presses the flat leaf spring 50, a washer 51 surrounding the valve stem 52 communicating the pressure of the spring 50 to the valve 45, a coiled spring 53 pressing against the top of the plate 46 further serving to maintain the 105 exhaust valve normally closed.

On the upward stroke of the piston the pressure of the fluid raises the valve 45 slightly against the pressure of the leaf spring 50, the fluid passing through the openings 48 and discharge orifice 54. If it 115 should happen, as is frequently the case, that a quantity of condensed gas in liquid form is forced into the compression chamber, the pressure of the piston upon this solid mass will put the coiled spring 53 120 under compression, the valve 45 moving to a greater extent than otherwise and providing more space in the upper end of the cylinder for the fluid in liquid form and affording a safeguard against damage to the 125 machine by the presence of an incompressible liquid mass.

A feature of notable importance in the construction and arrangement shown is in the provision of an annular surface 55 at 130

the outer end of the cylinder walls and an annular surface 56 on the cylinder head 13 facing the surface 55, with packing 57 between these surfaces and also between the 5 surface 56 and the upper edge of the ring 42, thus effectively sealing the head and cylinder walls against the escape of fluid and pressure while maintaining the relative position of the valve seat device to the cylinder 10 walls and piston end. This relative position is determined by the seat 41, which maintains the valve-seat device in its desired position independently of any packing, and the packing at 57 may be greater or less without 15 changing the relative position of the valve-seat device. This is important from various standpoints including this that the valve seat device may be positioned so close to the end of the piston on its upward stroke that 20 the highest efficiency of the device may be had, and this efficiency may be maintained without consideration of the thickness of the packing.

From Fig. 1 it will be noted that the 25 valve 23 on the piston will substantially fill the opening 44 of the valve seat device when the top surface 22 of the piston substantially comes into contact with the bottom surface of the flange 43 of the valve-seat device. It 30 is clear that if the valve-seat device rested upon packing instead of the firm shoulder 41 there would be danger of breakage of parts if the packing were not maintained sufficiently thick to space the piston from 35 the valve-seat device, and in practice heretofore in such devices there has always been provided a materially large space between the end of the piston and the discharge valve mechanism so as to provide for variations 40 in the thickness of the packing, thus reducing the efficiency of the device.

I contemplate as being within the present improvements various changes, modifications and departures from what is herein specifically illustrated and described, as indicated in the appended claims.

I claim:

1. In combination, a piston cylinder, a piston therein having a valve for the passage of fluid from one side of the piston to the other side thereof, a pitman pivotally mounted upon the piston, means for moving the pitman with a stroke movement and with a rocking movement, spring means for holding said valve in its normally closed position, and means under the control of the rocking movement of the pitman for opening said valve against the pressure of said spring means and for relieving the pressure thereof to permit the valve to close under the pressure of said spring means.

2. In combination, a piston cylinder, a piston therein defining a high-pressure side and a low-pressure side of the cylinder, a 65 valve carried by said piston, the valve hav-

ing a movement toward the high-pressure side to open the valve for the passage of fluid from the low-pressure side to the high-pressure side, spring means for holding said valve in its normally closed position, a pitman having a stroke movement and a rocking movement pivotally connected to said piston on its low-pressure side, connecting means including a lever and a cushioning spring therefor between said valve and said pitman and operated by the rocking movement of the pitman for forcing the valve open against the pressure of said spring means near the beginning of a piston stroke movement in the direction of the low-pressure side.

3. In combination, a cylinder, a piston therein, a pitman pivotally connected to the piston, the piston having an opening therethrough for the passage of fluid from one side of the piston to the other side thereof, a valve normally closing said opening, spring means for holding said valve in its normally closed position, a lever carried by the piston and operatively connected to the valve to open the valve when the lever is moved in one direction, and a valve pushing element operatively connected to the pitman adjacent to its pivotal connection to the piston and adapted to move said lever in only one direction and to open said valve on such movement, and to relieve the pressure of said spring means on the reverse movement of the piston to permit said spring means to close the valve.

4. In combination, a piston cylinder, a piston therein having a valve for the passage of fluid from one side of the piston to the other side thereof, a pitman pivotally connected to the piston, means for moving the pitman with stroke movements and with sidewise rocking movements, a lever fulcrumed at one end at one side of the piston, pushing means including a connection on the pitman for moving the other end of said lever, a spring cushion operatively between said lever and said valve, and spring means for closing said valve and moving said lever in return direction when the pitman moves with a stroke movement in a direction opposite to that on which the valve is opened.

5. Outlet valve mechanism for compressors comprising in combination means forming an annular valve seat surrounding a relatively large discharge opening, a plate-like valve resting thereon, said valve having a central stem, a plate-like valve guide seated at a fixed distance from said valve and being loosely mounted for movement in a direction away from said valve, said guide having discharge openings therethrough, said guide being loosely mounted on said stem, the movements of said valve being guided by said stem in said guide,

- a relatively strong spring pressing said guide in a direction toward said valve, and a relatively weak spring operatively between said guide and said valve, the arrangement being such that valve opening pressure upon said valve moves the valve first against the pressure of said relatively weak spring and greater pressure upon the valve moves the valve and said guide against the pressure of said relatively strong spring, and whereby said valve may tilt in response to unequal valve-opening pressure upon said valve.
6. In a compressor, the combination of a piston having a plate-like disc valve head on its inner surface outstanding substantially the thickness of the valve head from the

end surface of the piston, mechanically operated means for opening said valve on the suction stroke of the piston, outlet valve mechanism including a plate-like member having a fixed relation to the end of the piston stroke and having an opening therein slightly larger than and registering with said disc-valve head and being so positioned that at the end of the piston stroke said disc-like valve head is positioned in said opening, a valve covering said opening on the side thereof opposite the piston, and means including a spring for holding said secondly-mentioned valve yieldingly in closing relation to said opening.

WALTER W. ROBINSON.
